UNITED STATES PATENT OFFICE.

JOHN H. SHAW, OF NEW HAVEN, CONNECTICUT, ASSIGNOR TO SARGENT & CO., OF SAME PLACE.

SNAP-HOOK.

SPECIFICATION forming part of Letters Patent No. 340,830, dated April 27, 1886.

Application filed March 1, 1886. Serial No. 193,608. (No model.)

To all whom it may concern:

Be it known that I, JOHN H. SHAW, of New Haven, in the county of New Haven and State of Connecticut, have invented a new Improvement in Snap-Hooks; and I do hereby declare the following, when taken in connection with accompanying drawings and the letters of reference marked thereon, to be a full, clear, and exact description of the same, and which said drawings constitute part of this specification, and represent, in—

Figure 1, a perspective view; Fig. 2, a perspective view of the body as formed in casting with the side open; Fig. 3, a longitudinal central section showing a side view of the bolt and spring; Fig. 4, a transverse section forward of the lugs and open; Fig. 5, the same section closed.

This invention relates to an improvement in snap-hooks, and particularly to that class in which the body is of tubular shape, with a loop at one end and a hook at the other, and a bolt arranged to slide in said body, the said bolt moved by means of a thumb-piece, which extends outward through a longitudinal slot in the body or barrel, and a spring to hold said bolt against the end of the hook. In this class of snap-hooks it is desirable that the slot in the body should extend through substantially its whole length to allow the escape of water and dirt; but if the slot in the body extends through its entire length the bolt is liable to be pressed so far into the body upon the spring as to cause the spring to set.

The object of this invention is to preserve the opening, and yet avoid this difficulty; and it consists in constructing the sides of the body with ears, which, when the sides are bent toward each other to embrace the spring and bolt, will meet, and thereby form a bridge or stop, against which the thumb-piece on the bolt will strike, and thereby prevent the bolt from being pressed so far into the body as to set the spring.

A represents the body of the snap, which is preferably cast with its sides opened in U shape, as shown in Fig. 2, the depth of the sides such that when turned inward in the usual manner to inclose the bolt and spring they will leave a longitudinal opening between the two edges.

The body is constructed with a loop, a, at one end, and a hook, b, at the other end, in the usual manner. Preferably on each edge of the body and midway of its length a lug or projection, d, is formed, so that when the studs are turned toward each other the said lugs will form a bridge across the opening, as seen in Fig. 1. The bolt e is provided with a thumb-piece, f, adapted to slide longitudinally in the body, the thumb-piece extending upward through the forward portion of the slot. The spiral spring g is set into the body in rear of the hook, and takes a bearing at one end against the loop end of the body and at the other end against the bolt e. The spring and bolt are placed in the body, and the sides turned toward each other until the lugs d substantially meet. The spring and bolt are thereby held in position, and the lugs form a bridge or stop, against which the thumb-piece of the bolt will strike before the spring is pressed so close as to cause it to set. This interruption of the continuity of the slot does not materially detract from it as a means for keeping the spring clear and free; but because of its stopping the bolt in its opening movement it greatly increases the durability of the hook.

While I prefer to construct the body with a lug on each side, it will be understood that the lug may be arranged on one side only, as indicated in broken lines, Fig. 2.

I claim—

In a snap-hook, the combination of the body A, constructed with a loop, a, at one end, and with a hook, b, at the other end, the sides of the said body turned toward each other, but so as to leave a space between them longitudinally, the said space interrupted by a lug, d, midway of the length of the sides, with a spring, g, and bolt e in said body, the bolt provided with a thumb-piece extending out through the slot forward of the said lug, the said thumb-piece and lug operating to arrest the inward movement of the bolt, substantially as described.

JOHN H. SHAW.
